UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

TIME-CONTROLLED DEAD-LOCKING DEVICE.

1,337,928.

Specification of Letters Patent.

Patented Apr. 20, 1920.

Application filed December 16, 1919. Serial No. 345,333.

To all whom it may concern:

Be it known that I, ROLLIN C. LEWIS, a citizen of the United States, and a resident of Stamford, in the county of Fairfield and 5 State of Connecticut, have invented certain new and useful Improvements in Time-Controlled Dead-Locking Devices; and I do hereby declare the following to be a full, clear, and exact description of the invention, 10 such as will enable others skilled in the art to which it appertains to make and use the same.

This invention relates to an improvement in time controlled dead locking devices for 15 door locks and is designed particularly as an improvement on the construction disclosed in my application Serial Number 314,100, filed July 29th, 1919.

In the application above referred to, the 20 construction is such that the door may be locked for a predetermined time against all keys of the lock except a master key used in connection with a clerk's key, and at the expiration of such time be transformed by 25 the time mechanism into a lock operable by said clerk's key alone.

The object of this invention is to provide 30 means whereby the dogging means for the bolt can be actuated by the dial mechanism of a combination lock, or a pin tumbler cylinder lock used interchangeably and secured in place by the same means and in the same manner.

A further object is to provide simple and 35 easily operable means for proving the correctness of a changed combination.

With these and other objects in view my 40 invention consists in the parts and combinations of parts as will be more fully explained and pointed out in the claims.

In the accompanying drawings, Figure 1 is a view in rear elevation of a lock embodying my invention the cover plate and portion of the time mechanism of the lock being 45 omitted; Fig. 2 is a view partly in vertical section and partly in elevation of the construction shown in Fig. 1; Fig. 3 is a view in horizontal section through the dial mechanism; Fig. 4 is a view in section of the 50 holder for the tumblers, and also showing the manner of securing the holder in place; Fig. 5 is a view in section showing a pin tumbler lock substituted for the dial lock and Fig. 6 is a view in section through the 55 same.

10 represents a lock casing adapted to be secured to the inner face of a door, and adapted to carry the bolt, key actuated mechanism for retracting the bolt and the time mechanism for controlling the dead locking means.

The details of the time mechanism form no part of this invention hence only such features thereof as coöperate with my lock are shown and herein referred to.

The bolt 11 is mounted in openings in the opposite sides of the casing 10, so that either end thereof may be the locking end, and it may be shifted from its locked to its unlocked position when not deadlocked, by the 70 cam 12 of the pin tumbler lock 13, which is actuated by the clerk's key.

This bolt is provided at its top edge with a slot 14 the side walls of which are parallel for a short distance and then widen out, the 75 side walls 15 below the parallel portions being inclined as shown to be engaged by the cam 12 for shifting the bolt 11 longitudinally from its locked to its unlocked position or vice versa.

Mounted in the housing 16 at the upper part of the casing 10, are the spring pressed dogs 17 and 18 one of which enters the slot 14 for locking the bolt when the latter is projected at one side of the casing 10, and 85 the other coöperates with said slot for locking the bolt in its unlocked position.

When the bolt is projected to the right as shown in Fig. 1, the dog 18 enters the slot 14 for locking the bolt in its projected position, 90 and it is lifted and removed from the said slot by its contact with the end of the cam 12, which as before explained is operated by the clerk's key. When the bolt is retracted, dog 17 drops into slot 14 and holds the bolt 95 against movement until actuated by the clerk's key.

The bolt is also provided on its upper edge, in a plane in front of the slot 14, with the recess 19 to receive the lower end of the 100 deadlocking plunger 20 also mounted for movement in the housing 16. This recess 19 is in front of the plane of the dog 18 so that when the bolt is retracted the dog will ride on the top of the bolt at the rear of said 105 recess.

Plunger 20 is normally held in contact with the bolt by a spring, and it is provided on its rear face with an opening for a pin 21 on the rod 22, the said opening being 110

sufficiently large to permit of a slight lateral or rocking movement of the rod 22 as will be hereinafter explained. This rod is bent to clear the time mechanism of the lock and 5 is connected near its lower end by a pin 23, to the lever 24 pivoted to the frame carrying the time mechanism of the lock. This lever 24 which is of the bell crank variety, is pivoted intermediate its ends and its end 10 projects upwardly and terminates in a flat surface 25 which is in the path of movement of the pin 26 on the driving wheel 27 of the time mechanism, so that during a part revolution of this wheel, the pin 26 will contact 15 with the flat face 25 of lever 24 and turn the latter in a direction to lift the rod 22 and the plunger 20 connected with the said rod. The parts thus far described are substantially like the construction disclosed in my 20 application above referred to.

This lock like the one described in my application above referred to, is provided with means whereby the dead locking plunger can be disengaged from the bolt 25 by a master mechanism operable at any time prior to the disengagement of the dead locking plunger from the bolt by the time mechanism, thus leaving the latter free to be retracted by a clerk's key, and this mechanism may be either a combination lock actuated by a dial, or a pin tumbler lock. In 30 Figs. 2 and 3 of the drawing I have shown a pin tumbler lock 13 for retracting and projecting the bolt and a dial combination lock for lifting plunger 20 in advance of the operation of the time mechanism, but the construction of the lock is such, as will be now explained, that either a pin tumbler lock similar to the lock 13, or a combination lock actuated by a dial such as is shown, 35 may be used without any change in the construction of the lock, or one can be substituted for the other in the event a change should be necessary.

40 Secured by screws to the front face of the lock casing 10 is the holder 28 which houses the tumblers 29 of a combination lock and which also supports and guides the dial spindle 30, by which the tumblers are actuated in the well known manner.

55 Located in front of the holder 28 is the dish shaped plate 31 the edge or periphery of which rests against the inner face of the door, as clearly shown in Fig. 3, and is held there by the screw bolts 32 which pass through said plate and engage either the ring of a dial lock as shown in Fig. 3, or the cylinder of a pin tumbler lock as shown in Fig. 5. In other words I use the same holding means or plate for both the upper lock 13 and the lower lock, thus permitting me 60 to use either a dial combination lock or pin tumbler lock for releasing the dogging plunger 20 in advance of the operation of the time lock.

In the construction shown in the drawings, the lower end of rod 22 extends forwardly, then laterally toward the tumblers 29 and then forwardly, this forwardly projecting end 34 which constitutes the fence, 70 being held in contact with the peripheries of the tumblers by the spring 35, hence when the gatings of the tumblers are in alinement the fence 34 will enter the gating simultaneously and then by turning the dial in the 75 proper directions the fence and also the rod 22 of which the fence is a part, will be moved upwardly thus withdrawing plunger 20 from its recess in the bolt 11 and leaving the latter free to be then retracted by the 80 clerk's key.

When a dial combination lock is used, means must be provided for ascertaining or proving a new combination. The actual changing of the combination is accomplished in the same manner as in other combination locks. After the combination has been changed it should be proved and this may be done by mounting the laterally bent portion of the rod 22 on the shoulder 36, 90 cast integral with the casing 10 so that by pressing with a finger at the point 37 on rod 22, the latter will tilt or rock on its fulcrum 36 and carry its fence portion 34 against the outer tumbler of the series, or the tumbler nearest the dial, and away from the inner tumblers. As the tumblers are turned by the dial, the fence 34, which as above stated bears against the outer tumbler of the series will, as the latter is turned enter 95 the gating therein and thus hold it against further rotation. By now consulting the dial the letter or number upon which the outer tumbler is set can be ascertained. The other or inner tumblers of the series are 100 free to be turned and by now turning the dial in the opposite direction the gating in the next tumbler can be picked up in the same way and so on throughout the series of tumblers.

110 After the combination has been changed, the rod 22 is released thus permitting it to assume its normal position with its fence parallel to peripheries of all the tumblers and in position to enter the gating in the 115 said tumblers when the latter have been properly set up by the manipulation of the dial. After the fence has entered the gatings, a further turn of the dial turns the tumblers which lift the fence and the 120 rod 22 and thus withdraws the plunger 20 from its recess in the bolt.

If it be desired to use a pin tumbler lock, as in Fig. 5, instead of the dial tumbler lock, all the tumblers but the driving tumbler 38 are removed, and the connecting bar 39 of the pin tumbler lock 40 is entered in the slot 41 of the driving tumbler sleeve 42. This connects the driving tumbler 38 of the lock with the pin tumbler lock so that when 130

the latter is actuated by its key the dead locking plunger 29 will be disengaged from the bolt.

The time mechanism may be set to actuate the plunger 20 at any time within a certain period, and until that period has been reached and the plunger 20 withdrawn from its recess in the bolt, the latter will be absolutely deadlocked against all keys, 10 if the dial combination lock be used, or against all keys but the master key in the event a pin tumbler lock be substituted for the dial combination lock, so that it will be impossible for one having a clerk's key to 15 unlock the door while the latter is deadlocked by the plunger 20, but the latter may be withdrawn from the bolt at any time by the correct manipulation of the dial of the combination lock, or if a pin tumbler lock 20 be used, by the use of the proper key for such lock, after which the bolt may be retracted by the clerk's key.

It is evident that many slight changes might be resorted to in the relative arrangement of parts shown and described without departing from the spirit and scope of my invention. Hence I would have it understood that I do not wish to confine myself to the exact construction and arrangement of 30 parts shown and described but,

Having fully described my invention what I claim as new and desire to secure by Letters-Patent, is:—

1. In a lock, the combination of a casing, 35 a bolt, key mechanism for actuating same, time controlled mechanism for deadlocking the bolt against said key mechanism, and means for disengaging the time controlled deadlocking means from the bolt whereby 40 the latter may then be actuated by its key mechanism, the said disengaging means being secured against the outer face of the door by screw bolts carried by a plate adjacent the front of the lock casing and engaging 45 the rear face of said disengaging means.

2. In a lock, the combination of a bolt,

key mechanism for actuating the same, time controlled mechanism for deadlocking the bolt against said key mechanism, and means associated therewith and operable to interchangeably connect a dial combination lock or a pin tumbler lock with said time controlled dogging means whereby the latter may be actuated to release the bolt prior to the time set for its release by the time 55 mechanism.

3. In a lock, the combination of a bolt, key mechanism for actuating same, a deadlocking plunger for the bolt, a dial and tumblers, and means including the locking fence 60 for the tumbler for disengaging the plunger from the bolt, the said fence being mounted to be tilted sidewise to engage the tumblers and enter the gatings in the same as the latter are successively brought into 65 position and thus indicate to the operator the combination on which the lock has been set.

4. In a lock, the combination of a bolt, key mechanism for actuating the same, a 70 dial and tumbler mechanism, a plunger for deadlocking the bolt, and means actuated by the tumbler mechanism for moving the deadlocking plunger out of engagement with the bolt, thus leaving the latter free to be 75 actuated by its key mechanism.

5. In a lock, the combination of a bolt, key mechanism for actuating the same, a dial combination lock, a plunger for deadlocking the bolt and a combined tilting and 80 longitudinally movable rod intermediate the plunger and tumblers and actuated by the latter to disengage the plunger from the bolt.

In testimony whereof I have signed this 85 specification in the presence of two subscribing witnesses.

ROLLIN C. LEWIS.
